PRUNING SHEARS

Adolph J. Trapp, Southington, Conn., assignor to
The Peck, Stow & Wilcox Company, Southington, Conn., a corporation of Connecticut

Application December 9, 1938, Serial No. 244,748

6 Claims. (Cl. 30—237)

This invention relates particularly to pruning shears of the well known flat platen type. The invention consists of certain novel and useful features of improvement in the construction and arrangement of the essential parts.

One object is to provide certain improvements that will permit of rapid and economical production of a high-grade shear.

Another object is to provide a knife element that may be quickly and easily detached for replacement or sharpening without dismemberment of any of the other parts.

Another object is to make the effective length of the work supporting face of the platen correspond substantially to at least the effective length of the cutting edge of the knife.

Another object is to provide an adjustment that permits the platen face and the knife edge to be angularly adjusted relatively to each other so that when the shears are closed the cutting edge of the knife may be caused to bear from end to end on the platen.

The above and other objects will be apparent to anyone skilled in the art from a reading of the following description and an examination of the accompanying drawing, in which—

Fig. 1 is a side elevation of my improved shears shown as open;

Fig. 2 is a similar view showing the shears closed;

Fig. 3 is a section on the line 3—3 of Fig. 1;

Fig. 4 is an end view of the parts as shown in Fig. 2.

I have shown and will describe a preferred form of my invention, realizing that some changes and modifications may be made without departing from the spirit and scope thereof.

1 represents a long lever which may be shaped from wrought metal by dies to form at its rear a channeled grip portion. Forward of this grip the side flanges are widened to form broad parallel spaced bearing cheeks 1'—1' and forward of said cheeks the side flanges are extended to form two parallel spaced extensions 1"—1" upon which a platen 2 is mounted, the work supporting face of which platen is straight and flat, while the back forms a web 2' projecting between the extensions 1"—1" and clamped between them by any suitable means such as a clamp screw 3. 4 represents a short lever which may be drawn up from wrought metal by dies to form a channeled grip portion at the rear. The side flanges forward of the grip are extended and widened to form broad parallel bearing cheeks 4'—4' spaced sufficiently to straddle

and bear upon the outer surfaces of the bearing cheeks 1'—1' of the other lever. 5 is a pivot or stud penetrating the cheeks 1'—1' and 4'—4' to form a fulcrum for the levers 1—4. This pivot is located out of line with the straight work face of the platen for the purpose later described. 6 is a knife member having a straight cutting edge at its forward end and a tail 6' at its rear end. The knife member is guided in a definite plane by and between the bearing cheeks 1'—1' as the shears are opened and closed. When the knife member is in operative position, the tail 6' is in position to be engaged by the inner wall of the grip portion of the long lever 1. The knife member is pivotally connected intermediate its length to the cheeks 4—4 by a removable pin or bolt 7 at one side of the fulcrum pin 5. The inside cheeks 1—1 are provided with passages or slots 1'—1' of a size to provide free clearance for the body of the bolt 7 as the shears are opened and closed. The pivot 5 for the levers 1—4 is offset from the plane of the working face of the platen so that the knife and platen will approach each other obliquely to effect the well known draw-cut. 8 is a spring secured at its rear end to the grip portion of the lever 1, its free end pressing toward the grip of the other lever 4. Preferably this spring bears against the knife tail 6 so that it will not only hold the knife yieldingly in place but will also perform its usual function of opening the shears. 9 conventionally indicates a latch of any well known form such as commonly employed in pruning shears to hold them closed when not in use. The effective cutting edge of the knife and the effective length of the flat work supporting face of the platen correspond substantially so that the full length cutting function of the knife and a corresponding full length supporting function of the platen may be utilized.

In Fig. 2, showing the shears closed, the effective length of the platen and knife are seen to correspond. In Fig. 1, showing the shears opened, a portion of the flat work face of the platen is shown in dotted lines as retired between the cheeks 4'—4' ready to advance and crowd the work against the knife when the shears start to close and to follow it up while closing.

The platen and the knife are angularly adjustable relatively to each other. In this instance adjustment is effected by shifting the platen longitudinally on the extensions 1"—1". The sides of the platen which bear on said extensions 55

are formed on a slight arc as shown, and the supporting edges of the extensions are correspondingly shaped. Hence, by shifting the platen to and fro on the extensions the contact line 5 of the straight platen face may be angularly adjusted to coincide with the straight cutting edge of the knife when the shears are closed. By this means any variation that may occur in the alinement of the knife edge due to sharpening 10 or resharpening may be quickly and easily compensated for. The web of the platen should of course have a clearance slot 2" for the clamp screw 3 sufficiently large to permit the platen to be shifted sufficiently for adjustment purposes.

15 I claim:

1. Pruning shears comprising a knife member having a straight cutting edge at one end, a platen having a flat straight work face of a length substantially equal to at least to the length as 20 said cutting edge for cooperation therewith, means to move said knife cutting edge and platen obliquely toward and from each other as the shears are closed and opened, and a removable fulcrum pin for detachably connecting said knife 25 member at a point intermediate its ends to the end of the short lever and a fulcrum pin connecting the end of the short lever to the long lever at a point adjacent to said fulcrum pin.

2. Pruning shears comprising a long lever having a grip portion at its rear end, a platen supporting portion at its forward end and intermediate spaced parallel bearing cheeks, a platen having a straight flat work face carried by the forward end of said lever, a short lever pivoted 35 at one end to the first lever intermediate the length of the latter and out of line with the plane of the platen work face, a knife member having a straight cutting edge at its forward end for coaction with the platen work face and having a 40 tail at its rear end, a pin for detachably connecting the fulcrumed end of the short lever to said knife at a point between the cutting edge and the tail of the latter and at one side of the pivot for said levers, the tail of said knife being 45 adapted to overlap the inside of the short lever back of the fulcrum to be actuated thereby in a closing direction.

3. Pruning shears comprising a long lever having a grip portion at its rear end, a platen supporting portion at its forward end and intermediate spaced parallel bearing cheeks, a platen having a straight flat work face carried by the forward end of said lever, a short lever pivoted at one end to the first lever intermediate the 50 length of the latter and out of line with the plane of the platen work face, a knife member having a straight cutting edge at its forward end for coaction with the platen work face and having a tail at its rear end, a pin for detachably connecting the fulcrumed end of the short lever to said knife at a point between the cutting edge and the tail of the latter and at one side of the pivot for said levers, the tail of said knife being 55 adapted to overlap the inside of the short lever

back of the fulcrum to be actuated thereby in a closing direction, and a spring for yieldingly urging the tail of said knife toward the inside of the rear portion of said short lever and also tending to open said shears.

4. Pruning shears comprising a long lever having a channeled grip, the side flanges thereof merging into two parallel spaced bearing cheeks and continuing forwardly therefrom to form two spaced platen supporting extensions, a platen having a straight flat work face rigidly held on said extensions, a short lever having a channeled grip portion, the side flanges thereof merging into two parallel bearing cheeks at the forward end spaced to straddle and bear upon the outside surfaces of the first mentioned cheeks, a pivot connecting said levers by passing through all four of said cheeks at a point out of line with the work face of said platen, a knife member having a straight cutting edge at one end and a tail at the other end, the rear portion of said knife member being insertible between and laterally supported by said spaced cheeks of the long lever the tail of said knife member extending rearwardly to overlap the inside of the grip portion of the short lever back of said pivot, a removable pin operatively connecting the cheeks of the short lever with an intermediate portion of the knife and at one side of said fulcrum pin, the cheeks of the long lever having enlarged passages to provide free working clearance for said knife connecting pin as the shears are opened and closed.

5. In a pair of pruning shears, two pivotally connected levers, a knife member movable to and fro by one lever, a platen member having a flat work face mounted on the other lever for movement toward and from said knife, said mounting comprising, a forward extension on the last mentioned lever having an arc-shaped seat for 40 said platen, the latter being shiftable thereon to control the line of contact of said work face relatively to the knife edge when said parts are brought into contact on closing the shears.

6. Pruning shears comprising a knife member having a cutting edge at its forward end and a tail at its rear end, a platen having a flat work face facing toward the cutting edge of the knife for cooperation therewith, a long lever carrying said platen at its forward end and having a grip at its rear end, a short lever having a grip at its rear end, said short lever being fulcrumed at its forward end to said long lever at a point between the grip and the platen carrying portions of the latter and out of line with the plane of the platen face, with means directly connecting said knife member between its cutting edge and tail to said short lever, the tail of said knife member overlapping the inner side of the grip of said short lever whereby it may be moved thereby as the grip portions of both levers approach each other.

ADOLPH J. TRAPP.
